(57) **CLAIM**

The ornamental design for a ceiling mount as shown and described.

DESCRIPTION

FIG. 1 is a perspective view of a ceiling mount.

FIG. 2 is a top view of the ceiling mount shown in FIG. 1.

FIG. 3 is a bottom view of the ceiling mount shown in FIG. 1; and,

FIG. 4 is a front view of the ceiling mount shown in FIG. 1. The broken line showing of ceiling mount is included for the purposes of illustrating portions of the article and forms no part of the claimed design.

1 Claim, 4 Drawing Sheets
